HIGHWAY CROSSING SIGNAL SYSTEM

Filed June 20, 1941

FIG. 1.

UNITED STATES PATENT OFFICE

2,366,690

HIGHWAY CROSSING SIGNAL SYSTEM

Walter C. Alexander, Oswego, N. Y., assignor to
General Railway Signal Company, Rochester,
N. Y.

Application June 20, 1941, Serial No. 398,940

5 Claims. (Cl. 246—130)

The present invention relates in general to highway crossing signalling systems such as used where highways cross railways, and has more particular reference to a system of this type which is of particular advantage under certain wayside conditions.

Where a highway crosses a railway closely adjacent to a railway siding leading from the railway, there may be insufficient distance between the highway and the siding to give sufficient time of warning to highway traffic of an approaching train if the warning signal is not initiated ahead of the siding. In such cases, the effect of a train approaching and crossing the highway, and that of a train approaching merely to the siding and then engaging in switching operations, is the same with regard to the signal being initiated and continued. While the signal is discontinued when the crossing train clears the crossing, the switching train would ordinarily continue the signal for so long as the switching operations continue. This is very undesirable since it teaches highway traffic to disregard such signals because many times they indicate no danger whatsoever, and thus lays the way open to grave dangers.

In accordance with the present invention, a means is provided for initiating the signal upon the approach of a train, and for continuing it until the train clears the highway if the train passes through. However, if the train engages in switching operations, or remains unduly long adjacent the siding, the signal which has been initiated is discontinued after a short period of time, whereby to avoid educating the public to ignore such warning crossing signals.

Further objects, purposes and characteristic features of the present invention will appear as the description progresses, reference being made to the accompanying drawing showing solely by way of example, and in no way in a limiting sense, two forms which the invention may assume. In the drawing:

Fig. 1 is a wholly schematic showing of one embodiment of the invention.

Fig. 2 is a wholly schematic showing of a second embodiment of the invention.

Referring now to the drawing, and first to Fig. 1, there is here represented a stretch of single track constituted by track rails 31, separated into isolated sections by usual insulating joints 41, to constitute sections 1 and 2. A highway 50 crosses the track rails at the exit end of section 2. At each side of the track rails and alongside the highway is positioned a warning signal Sig.,

each of which in the present showing comprises two lamps as shown whereby if the lamps of each signal are alternately energized, and deenergized, a swinging or flashing light signal is given which strongly arrests attention.

Across the entrance end of section 1 is connected a track battery 61 connected in series with an adjustable resistance 71, while across the other end of this section is connected a track relay 1T.

10 Across the entrance end of section 2 is connected a track battery 8 in series with an adjustable resistance 9, and a contact finger 10 and front point of track relay 1T, whereby when relay 1T is retracted section 2 is deprived of track current. Across the exit end of section 2 is connected a track relay 2T.

15 A siding constituted by track rails 11 is shown as leaving the main track within section 1 whereby an east bound train, traffic being considered,

20 in this embodiment, in one direction only, as indicated by the arrow 12, can either proceed and pass over the highway or can remain in section 1, and the adjacent part of the siding for switching operations.

25 For controlling the signal system, there is employed a time element device which includes a motor M having a shaft 13, carrying signal control cams 14 and 15. These cams have rises, as shown, each cam having a rise extending throughout approximately 180°, with the cams positioned on the shaft so that the rises are displaced approximately 180° from each other. The cams operate on pushers 16 and 17, to move contacts 18 and 19, between associated front and back points, 30 whereby to cause the signals to swing or flash, as will appear more clearly below.

35 Motor M through its shaft 13, operates a gear train 20, for operating a timing wheel 21, having a rise 22 thereon, which when rotated to the

40 proper position, controls a contact 23, so as to close it on its back point. This timing wheel 21 is carried on an arm 24, pivoted at 25, and carrying an armature 26 which, when attracted by a clutch magnet CM, moves the timing wheel into 45 mesh with the gear train to thereby cause the motor shaft to turn the timing wheel. When the clutch magnet is deenergized the timing wheel is moved out of engagement with its drive and is returned to its initial position by any desired 50 means, as, for example, a weight 27 thereon. In the control system is involved a stick relay 1S which operates at times to control energization and deenergization of clutch magnet CM.

Let us now assume that a train approaches the 55 highway and enters section 1. Track relay 1T

releases, whereby to cut trackway energy off of section 2 and cause the release of track relay 2T. Upon 2T making up its back point, the signals Sig. and the motor M are energized. The circuit for energizing the motor includes contact finger 28 and back point of relay 2T, and wires 29 and 30. The circuits for energizing the signals include one side of a source of energy, contact finger 28 and back point of relay 2T, wires 29, 31, 32 and 33; then in multiple through the two lamps of the right-hand signal to wire 36, and through wire 34, the lamps of the other signal and wire 35 to wire 36, and thence through wires 37 and 38 to the other side of the source of energy. These lamps, however, are not energized in series, since each of the control contacts 18 and 19 are connected as shown to shunt out first one lamp and then the other of each signal as each contact moves from front to back point, and reverse.

The operation of the signal is similar to that which occurs when a usual flashing relay is employed for the control of the signal as, for example, in the patent to O. S. Field, No. 1,969,065, granted August 7, 1934.

For example, with relay 2T down, a circuit is completed for energizing the right-hand lamp of the left-hand signal, which circuit includes contact finger 28 and back point of relay 2T, wires 29, 31 and 32¹, contact finger 18 and front point, wires 40 and 41, the right-hand lamp of the left-hand signal, and wires 35, 36, 37 and 38. The left-hand lamp of the left-hand signal is not energized, because it is shunted out by a shunt which includes wires 32, 33, 34 and 42. In a similar manner the right-hand signal has one lamp only energized under the conditions shown. Upon contacts 18 and 19 shifting respectively to their back and front points, the previously shunted out signal lamps will be energized and the other lamps will be deenergized.

The signal does not continue to flash, however, beyond a short period of time, unless the train proceeds into section 2. This result is due to the timer operating to cut the signal out after a short period of time, as, for example, 20 seconds. Upon the release of relay 1T a circuit is completed for energizing clutch magnet CM, which circuit includes contact finger 43 and back point of relay 1T, and contact finger 44 and back point of relay 1S. This results in meshing the timing wheel to the gear train, and after a short time contact 23 of the timer closes to thereby energize relay 1S through a circuit which includes contact finger 43 and back point of relay 1T, contact finger 23 and back point, and the winding of relay 1S.

The picking up of relay 1S closes a shunt around contact finger 10 of relay 1T, which shunt includes contact finger 45 and front point of relay 1S; whereby to apply track energy to section 2 and cause the picking up of track relay 2T. The picking up of track relay 2T deenergizes both the motor and the signals, while the picking up of relay 1S deenergizes the clutch magnet, and completes a stick circuit for relay 1S which includes contact finger 43 and back point of relay 1T, and contact finger 44 and front point of relay 1S.

Thus, if the approaching train remains in section 1 for any length of time, and for any reason, as, for example, for switching operations, the signal is initiated, and is then discontinued after a short period of time with track relay 1T released, track relay 2T is attracted, and stick relay 1S stuck up through track relay 1T released.

If, however, the train proceeds to the crossing, the timer will not have run out by the time the

train enters section 2, whereby relay 2T is shunted and remains down even after the timer has completed its operation. Thus, the signal continues to be displayed although the timer is disengaged and the signal continues until the rear end of the train clears the crossing.

If the approaching train should perform switching operations, or for any other reason remain for some time in section 1, and then pass through section 2 and over the highway, its speed will necessarily be so low that adequate time of signal warning will be given.

The form just described (Fig. 1) is arranged for one-way traffic only, but the system lends itself, with modifications, to the form where a crossing can be approached from either direction on the single track. Such a system is shown in Fig. 2 wherein a stretch of single track is shown, separated into isolated sections 3 and 4 at one side of a highway 50, and sections 5 and 6 at the other side of the highway, with a siding 51 leaving section 3 and a siding 52 leaving section 6.

The sources of energy and the connections thereof for some of the sections have not been shown since they are the same as in Fig. 1, and the control thereof is the same.

In this form of the invention, the two track relays 4T and 5T, connected across ends of sections 4 and 5, are interlocked, as indicated, in a usual manner, as, for example, in the patent to O. S. Field, No. 1,824,131, granted September 22, 1931. Although two-way traffic is cared for, a single timing means and motor means is employed and suitable interlock means is provided to avoid dangerous conditions and signal failures in the event of simultaneous occupancy of detector sections at the two sides of the highway.

As before, if a train approaching the highway, as, for example, an east bound train, enters section 3, its track relay 3T releases to cause the release of track relay 4T, and energization of the signals and the operating motor M1 as in the Fig. 1 form of invention.

Likewise, the clutch magnet CM1 is energized through a circuit which is interlocked with the sections at the other side of the highway, and which includes contact finger 54 and back point of relay 3T, contact finger 55 and back point of relay 4S, contact finger 56 and front point of relay 6T, and contact finger 57 and back point of relay 3T. This starts the timer as before, and after it has completed its cycle, the timer contacts 58 and 59 close on their back points, the contact finger 58 operating to close the circuit for energizing relay 4S through a circuit including contact finger 54 and back point of relay 3T, and timer contact finger 58 in closed position. Relay 4S then sticks up through contact finger 54 and back point, and its own contact finger 55 and front point.

Upon a train approaching the highway from an easterly direction, as, for example, entering section 6, the operation is the same as described just above. Thus, for a train crossing the highway from either direction, the operation is as described with respect to Fig. 1 although but a single timer and control motor is employed.

Consider now the situation where a train occupies section 3, and is, perhaps, engaged in switching operations, and during this occupancy a train enters section 6, proceeding in a westerly direction.

Let us first assume that the train enters section 6 after the timing cycle initiated by the occupancy of section 3, has been completed. In these

circumstances, relay 3T is retracted, relay 4S is stuck up through relay 3T down, the clutch magnet CM1 is deenergized and relay 4T is picked up and thus deenergizes the signals and the motor. The occupancy of section 6 deprives section 5 of track energy with the result that interlocked relay 5T releases and makes up its back points, to energize the signals and the motor. The clutch magnet CM1 is also energized through a circuit including contact finger 61 and back point, contact finger 62 and back point, contact finger 56 and back point, contact finger 63 and front point, and contact finger 57 and back point. Thus, it is seen that, despite the fact relay 3T is released, due to the switching operations taking place, the timer is initiated as usual because stick relay 4S at this time is energized.

Accordingly, whether the train proceeds across the highway, or whether it engages in switching movements, the operations proceed as if there were no occupancy of section 3.

On the other hand, if the train enters from the east before the operation of the timing period initiated by the occupancy of section 3, the operation is somewhat different. The release of track relay 6T opens the circuit of the clutch magnet CM1 to discontinue the timing and prevent the subsequent picking up of relay 4S. Thus, energy is not restored to section 4 since the shunt around the front contact of relay 3T is not closed so that relay 4T does not pick up. Accordingly, the signals remain energized and likewise, so does the motor. Thus, the signal continues to be displayed as the west bound train approaches and passes over the highway, all due to the released condition of relay 4T. The other interlocked relay 5T, although deenergized while the train is occupying one or both of blocks 6 and 5, cannot make up its back point, but is, so to speak, "on the latch." These interlocked relays operate in the conventional manner, whereby, upon the first releasing, the second, if deenergized, is latched up against making up its back point and cannot make up its back point until after the first relay has been reenergized, and then the second relay has been reenergized.

The operation, as described above, is repeated in similar manner if section 6 be occupied when an east bound train enters section 3.

Thus, in the forms of invention described above, in Fig. 1, a single signal operating means and timing means is effective to care for two types of train movements, one in which the train approaching the highway proceeds at reasonable speed to cross the highway, and the other in which the train approaching the highway fails to cross the highway at all but engages in switching operation or the like, and then either backs away from the highway or proceeds to cross the highway at a very low speed. In the form of Fig. 2, this same plurality of different train movements occurring in either direction and either separately or simultaneously is cared for again by a single motor and single timing means for controlling the signals.

While light signals have been shown, it is obvious that other types of signals can be employed as likewise various other means for operating the timing wheel can be used if proved expedient.

The above rather specific description of two forms of the present invention is given solely by way of example, and is not intended in any manner whatsoever, in a limiting sense. It is to be understood that various modifications, adaptations, and alterations can be applied to meet the

requirements of practice without in any manner departing from the spirit and scope of the invention except insofar as limited by the appended claims.

- 5 Having described my invention, I now claim:
1. In a crossing signal system, in combination, a stretch of track intersecting a highway, a signal at the intersection, an approach section spaced from the highway, a local section connecting the intersection and the approach section, a track circuit including a track relay associated with each section, a front point of the track relay of the approach section in the track circuit of the local section, an energizing circuit for the signal including a back point of the local section relay, a mechanical cut-out timing means effective a predetermined time after occupancy of the approach section to close a shunt across the front point of the approach section relay, mechanical flashing means movable to alternately open and close the signal circuit, a motor, means operatively connecting the motor to both the timing means and the flashing means, and an energizing circuit for the motor closed upon occupancy of either of the track sections.
2. In a crossing signal system, in combination, a stretch of track intersecting a highway, a signal at the intersection, an approach section at each side of, and spaced from, the highway, a local section connecting the highway and each of the approach sections, a track circuit, including a track relay, for each section, a front point of the track relay for each of the approach sections in the track circuit of the adjacent local section, energizing circuits for the signal and each including a back point of a local section relay, a single normally ineffective timing means made effective a predetermined time after occupancy of either of the approach sections to close a shunt across the front point of the adjacent approach section relay, mechanical flashing means movable to alternately open and close the signal circuits, a motor, means operatively connecting the motor both to the timing means and the flashing means, and energizing circuit means for the motor closed upon occupancy of any of the track sections.
3. In a highway crossing signal system, in combination, a stretch of track intersecting a highway, a signal at the intersection, at least one timing section of track spaced from the highway, a siding leading from the timing section, a control section of track extending between the timing section and the intersection, a combined cut-out timer and signal flashing means including, a motor, a cut-out timing member operable by the motor, mechanical signal flashing means operably connected to the motor, control means effective immediately, upon occupancy of the timing section, and/or the adjacent portion of the siding, to energize the motor and signal and cause the timer to operate through a timing cycle and cause the signal to flash, and means to deenergize the motor and signal upon completion of the timing cycle and despite any then-occupancy of the timing section and/or the adjacent portion of the siding, a part of said control means being connected to the control section and effective, upon its section being occupied, to energize the motor and signal and cause the signal to flash so long as the control section is occupied.
4. In a highway crossing signal system, in combination, a stretch of track intersecting a highway, a signal at the intersection, a timing sec-

tion of track spaced from the highway, a siding leading from the timing section, a control section of track extending between the timing section and the intersection, a combined cut-out timer and signal flashing means including a motor, a cut-out timing member operable by the motor, a normally inoperative clutch between the motor and timing member, mechanical signal flashing means operably connected to the motor, control means effective immediately, upon occupancy of the timing section, and/or the adjacent portion of the siding, to energize the motor and signal and make the clutch operative and so cause the timer to operate through a timing cycle and cause the signal to flash, and means to deenergize the motor and signal and make the clutch inoperative upon completion of the timing cycle and regardless of the then-occupancy of the timing section and/or the adjacent portion of the siding, a part of said control means being connected to the control section and effective, upon its section being occupied, to energize the motor and signal and cause the signal to flash so long as the control section is occupied.

5. In a crossing signal system; in combination, a stretch of track intersecting a highway; a signal at the intersection; an approach section at each side of and spaced from the highway; a

local section connecting the highway and each of the approach sections; a track circuit, including a track relay, for each section, the track relays for the local sections being interlocked so that one responds only to one direction of train movement and the other responds only to the opposite direction of train movement a front point of the track relay for each of the approach sections being included in the track circuit of the adjacent local section; energizing circuits for the signal and each including a back point of a local section track relay; a normally deenergized stick relay for each side of the crossing; a single normally deenergized timing means; an energizing circuit for each stick relay controlled by the single timing means; a first pair of energizing circuits for an essential portion of the timing means including respectively a back point of one approach section relay and a front point of the other approach section relay; and a second pair of energizing circuits for said portion of the timing means including respectively a back point of an approach section relay, a back point of the other approach section relay and a front point of the stick relay associated with said other approach section relay.

WALTER C. ALEXANDER.
